DESIGN FOR A BOX

Frank McIntosh, New York, N. Y., assignor to
Lentheric, Incorporated, New York, N. Y., a
corporation of New York

Application September 30, 1941, Serial No. 103,570

Term of patent 3½ years

To all whom it may concern:

Be it known that I, Frank McIntosh, a citizen of the United States, residing at New York city, in the county of New York and State of New York, have invented a new, original, and ornamental Design for a Box, of which the following is a specification, reference being had to the accompanying drawing, forming part thereof.

In the drawing:

Figs. 1, 2, and 3 are, respectively, a top plan view, front elevational view, and rear elevational view of a box embodying my new design; and white and black respectively represent relatively light and relatively dark colors.

I claim:

The ornamental design for a box, substantially as shown and described.

FRANK MCINTOSH.
